SLIPPER SOCK

Martha P. Hiestand, Princeton, Wis., assignor to
The Handcraft Company, Inc., Princeton, Wis.,
a corporation of Wisconsin

Application July 25, 1951, Serial No. 16,022

Term of patent 14 years

(Cl. D47—7)

To all whom it may concern:

Be it known that I, Martha P. Hiestand, a citizen of the United States, residing at Princeton, Green Lake County, State of Wisconsin, have invented a new, original, and ornamental Design for a Slipper Sock, of which the following is a specification, reference being had to the accompanying drawing, forming a part hereof, and wherein:

Fig. 1 is a side elevational view of a slipper sock, showing my new design;

Fig. 2 is a front elevational view thereof; and
Fig. 3 is a rear elevational view of the same.

The essential features of my design reside in the parts shown in full lines.

I claim:

The ornamental design for a slipper sock, as shown and described.

MARTHA P. Hiestand.
